INVENTOR.

Margaret W. Ean,

By her Attorney

Geo. H. Smith,

UNITED STATES PATENT OFFICE.

MARGARET W. EAN, OF NEW YORK, N. Y.

DESIGN FOR A COLLAR-STIFFENER.

53,896.

Specification for Design.

Patented Oct. 7, 1919.

Application filed April 5, 1919. Serial No. 287,837. Term of patent 7 years.

To all whom it may concern:

Be it known that I, MARGARET W. EAN, a citizen of the United States, residing in the borough of Manhattan, city, county, and State of New York, have invented a new, original, and ornamental Design for Collar-Stiffeners, of which the following is a specification, reference being had to the accompanying drawing, forming part thereof.

2, an edge view of a collar stiffener, showing my design.

I claim:

An ornamental design for a collar stiffener, as shown.

MARGARET W. EAN.

Witnesses:

GEO. WM. MIATT,
DOROTHY MIATT.
